(57) **CLAIM**

The ornamental design for an oxygenator with integrated blood reservoir as shown and described.

DESCRIPTION

1. Oxygenator with integrated blood reservoir

1.1 : Perspective

1.2 : Front

1.3 : Back

1.4 : Top

1.5 : Bottom

1.6 : Right

1.7 : Left

Fig. 1.1 is a perspective view of the oxygenator with integrated blood reservoir; fig. 1.2 is a front view thereof, fig. 1.3 is a rear view thereof; fig. 1.4 is a top view thereof, fig. 1.5 is a bottom view thereof; fig. 1.6 is a right view thereof; and fig. 1.7 is a left view thereof.

The portion of the design shown colored solid black is for the purpose of illustrating portions of the oxygenator with integrated blood reservoir and forms no part of the claimed design.

(Continued)

The broken line showing in the figures is for the purpose of illustrating portions of the oxygenator with integrated blood reservoir that forms no part of the claimed design.
